UNITED STATES PATENT OFFICE

WILLIAM FRANK M. HAWE, OF PITTSBURGH, PENNSYLVANIA, ASSIGNOR TO ADAMS BROS. MFG. CO., INC., A CORPORATION OF PENNSYLVANIA

DESIGN FOR A GAS RADIANT HEATER

Application filed May 14, 1930. Serial No. 35,637. Term of patent 7 years.

To all whom it may concern:

Be it known that I, WILLIAM FRANK M. HAWE, a citizen of the United States, residing at Pittsburgh, in the county of Allegheny and State of Pennsylvania, post-office address No. 1500 North Avenue West, in said city, have invented a new, original, and ornamental Design for Gas Radiant Heaters, of which the following is a specification, reference being had to the accompanying drawing, forming a part thereof.

Figure 1 of the drawing is a front view, and Figure 2 is a side view of the article showing my new design.

I claim:—

The ornamental design for a gas radiant heater as shown.

W. FRANK M. HAWE.
